UNITED STATES PATENT OFFICE.

WILLIAM P. HAMMOND, OF ROCKPORT, MASSACHUSETTS, ASSIGNOR TO TRIUMPH
COUCH BED CO., OF BOSTON, MASSACHUSETTS, A CORPORATION.

COUCH-BED.

1,038,879.

Specification of Letters Patent. Patented Sept. 17, 1912.

Application filed July 24, 1911. Serial No. 640,266.

To all whom it may concern:

Be it known that I, WILLIAM P. HAMMOND, a citizen of the United States, and a resident of Rockport, in the county of Plymouth and Commonwealth of Massachusetts, have invented certain new and useful Improvements in Couch-Beds, of which the following is a specification.

This invention relates to that class of couches wherein two superposed bed-sections are so disposed that upon the pressure of a person's foot upon a suitable lever or treadle, one of said sections can be moved off from and to one side of the other to comprise a bed of double the width of the couch; while the pressure of the foot upon another treadle will cause said sections to return to their superposed position. Couch-beds of this character usually have the inner edge of the movable bed-section supported upon the upper ends of swinging levers pivoted at their lower ends to the stationary sections, one of said levers having two toggle-joints the buckling of one of which will swing the levers, and hence the movable section with them, in one direction, while the buckling of the other toggle-joint will move said parts in the opposite direction. Such toggle-joints have, however, proved unsatisfactory for several reasons. First, many users of the couch-bed preferred, when they were standing in front of the same, to open or close the sections by applying their hands directly to the movable section; but in attempting to do this found themselves prevented by the failure of the unflexed toggle joint to yield to the pressure of its connected lever. This obliges them to walk around to the proper end of the couch-bed every time they want to change the arrangement of the same. Secondly, children or other inexperienced persons are liable to rest a foot directly upon the toggle-joint instead of upon the treadle provided, when shifting the movable bed-section, with the result of having such foot badly pinched or cut by the shearing action of the toggle joint.

My invention consists in substituting for the objectionable joints an arrangement comprising in each case a lever arm and a flexible link so disposed as to enable the movable bed-section to be shifted in practically the same manner as above recited, while wholly eliminating the objections referred to.

Referring to the drawings forming part of this specification, Figure 1 is a perspective view of one end of a couch-bed embodying my invention. Fig. 2 is a detail view on a larger scale of my method of attaching the flexible links to the actuating lever. Fig. 3 is a sectional view of the attaching device, showing related parts. Fig. 4 is a detail sectional view shown upon a larger scale of my preferred form of the invention. Fig. 5 is a detail view of the collar forming a part thereof.

As illustrated in Fig. 1, the movable bed-section 1 rests at its rear edge upon the end-bars 2 of the stationary section 3, and at its front is supported by legs 4 provided with casters 5. At each end of the stationary section is a swinging lever 6 fixed to a rock-shaft 7 rotatably supported in the end-bars 9. The free ends of said levers are pivoted to the rear edge of the movable section at 10, and between said levers is extended the brace bar 11 running parallel with said shaft, and serving to brace said levers against the strain of the inner edge of the bed bottom fabric of said movable section. By forcibly moving said levers 6, the rear side of the movable bed-section is carried from the rear side to the front or vice versa of the stationary bed-section, the front of the movable section sliding in the same directions upon its casters 5. For swinging said levers, a lever arm 12 is pivoted at each side of one of said levers 6, preferably to the posts 13 of the stationary bed-section. Each arm has a foot-piece or elbow 14 at its free end by means of which to forcibly swing the same downward by the convenient application of the foot thereto; and to such free end is attached a flexible connection, preferably a chain 15 the other end of which is attached to said lever. In the first attempts to attach these chains to the lever 6, they were swiveled directly thereto; but this was soon found to be highly objectionable, in as much as the chains frequently became entangled and caught in shortened positions which acted to keep the movable section from reaching its proper positions; either as a couch or a bed. I eventually found that by attaching the chains to a collar freely rotatable upon the brace-bar, this objection was wholly overcome. This collar 16 is formed with oppositely positioned eyes 17, as shown in Figs. 2 and 3, with which the 105 110

chains are engaged. To keep said collar in place on the brace rod 11, a stationary collar 19 is put thereon, as shown in Fig. 3.

It is evident that the flexible links 15 are entirely free of the objections found to exist in connection with the toggle-joints formerly employed. Should the person trying to adjust the bed put his foot upon either the arm 12 or chain 15 and then press downward thereon for adjusting the couch-bed, there can no possible harm arise therefrom since the flexible link or chain will simply wrap about the foot more or less and not injure it in the least. Such a bed-shifting toggle arrangement can be located at each end of the bed, if desired, and the operation of one not be in danger of interference from the other; and if either one or both arrangements are provided, neither can interfere with shifting the movable bed-section by hand.

In my preferred construction, shown in Figs. 4 and 5, the lever arms 12 are of cast metal, with the foot-engaging projections 14 carried in each case by an elbow 18. The collar 16 is here not formed with eyes 17, but with oppositely positioned ears 20 each carrying a headed pin 21 engaged by an end of a chain 15; similar headed pins 22 being supplied to the lever arms for the opposite ends of the chains. The chains themselves are not of the wrought metal type indicated in Figs. 1 to 3, but are of the well known kind stamped from sheet metal each link of which is doubled over into engagement with the preceding link, and hence much less expensive than the other type of chain.

What I claim as my invention and for which I desire Letters Patent is as follows, to wit:—

1. The combination of a stationary bed-section, a movable bed-section, lever arms pivoted to the ends of the stationary bed-section and supporting the rear of the movable bed-section, a bar attached at its ends

to intermediate points of the lever arms, a treadle arm pivoted to an end of the stationary bed-section at each side of the lever arm thereat, a collar loosely mounted on said bar close to the lever arm between said treadle arms, and chains attached to opposite points of said collar and to the free ends of the treadle arms.

2. The combination of a stationary bed-section, a movable bed-section, lever arms pivoted to the ends of the stationary bed-section and supporting the rear of the movable bed-section, a bar attached at its ends to intermediate points of the lever arms, a treadle arm pivoted to an end of the stationary bed-section at each side of the lever arm thereat, a collar rotatably mounted on said bar near the lever arm located between said treadle arms, said collar having diametrically opposite radial projections, and chains attached to said projections and to the free ends of the treadle arms.

3. The combination of a stationary bed-section, a movable bed-section, lever arms pivoted to the ends of the stationary bed-section and supporting the rear of the movable bed-section, a bar attached at its ends to intermediate points of the lever arms, a treadle arm pivoted to an end of the stationary bed-section at each side of the lever arm thereat, a collar rotatably mounted on said bar near the lever arm located between said treadle arms, said collar having diametrically opposite radial projections, a headed pin projecting from each said projection parallel with said bar, a headed pin projecting from the free end of each treadle arm parallel with said bar, and chains terminally attached to said headed pins.

In testimony that I claim the foregoing invention, I have hereunto set my hand this 8th day of June, 1911.

WILLIAM P. HAMMOND.
